UNITED STATES PATENT OFFICE.

HARRY J. KRAMER, OF BOSTON, MASSACHUSETTS.

METHOD OF CHARTING DRESS-PATTERNS.

1,098,736.

Specification of Letters Patent.

Patented June 2, 1914.

Application filed February 6, 1913. Serial No. 746,496.

To all whom it may concern:

Be it known that I, HARRY J. KRAMER, a citizen of the United States, residing at Boston, county of Suffolk, State of Massachusetts, have invented an Improvement in Methods of Charting Dress-Patterns, of which the following description, in connection with the accompanying drawing, is a specification, like characters on the drawing 10 representing like parts.

This invention relates to a method of laying out a garment pattern, and has for its object to provide a novel method by which the front, back and shoulder lines of the 15 garment pattern can be laid out and determined from angular measurements based on the circumferential measure of the armhole and on the cross back measurements.

I will first describe one embodiment of my 20 invention and then point out the novel features thereof in the appended claims.

Referring to the drawings, Figure 1 is a diagram view showing the method employed for laying off the lines of the front and back 25 portion of a garment pattern; Fig. 2 is a view showing a plate provided with the measurements for different sizes of garments; Fig. 3 is an enlarged section on the line $x-x$, Fig. 2; Fig. 4 is a diagram showing 30 the outline of the sections of the body and skirt portion of a particular garment pattern made in accordance with this invention; Fig. 5 shows the manner of grouping the skirt portions of the garment pattern to 35 provide for locating the position of the bottom line of the skirt.

In carrying out my invention I first take the circumferential measure of the armhole of the person for whom the garment is being 40 made and then determine the shoulder line and the cross back line by angular measurements based on the armhole size and cross back measure of said person. In order to give a clear understanding of the invention

45 I will first refer to the diagram shown in Fig. 1. After taking the circumferential measure of the arm-hole I draw on the paper, cloth, or other material from which the pattern is to be made, a base line 1-2, then I lay off on this line two points 3-4, which are a distance apart equal to one-fourth of the above armhole measure, and then lay off another point 5 a distance from the point 3 also equal to one-fourth of the 50 armhole measure. I also measure off on the

base line 1-2 from the point 3 a distance equal to two-thirds of the armhole measure thereby to secure the point 7. This gives the points 5, 3, 4 and 7 on the base line 1-2. The points 3 and 4 are the points for opposite sides of the armhole which is drawn in, as will be presently described, and the points 5 and 7 are the base points from which the shoulder lines are drawn. After thus determining the points 5 and 7 the shoulder 65 line 5-6 is drawn at an angle of approximately 34° from the base line 1, and the other shoulder line 7-8 is drawn from the point 7 at approximately 17° from the base line. 70

In order to get the armhole I first lay off on the base line 1-2 a distance from the point 3 equal to one-third of the armhole size, thus defining the point 11. From the point 11 a line 11-12 is drawn at an angle 75 of approximately thirteen and a half degrees from the base line 1 below the latter, and a line 4-13 is drawn from the point 4 at an angle of 27° from the base line below the latter. The contour of the armhole is then 80 drawn in by first drawing the arc 3-9 from the point 7 as a center, then drawing the arc 3-12 from the point 11 as a center; drawing the arc 12-13 from the point 14 as a center where the two lines 11-12 and 4-13 cross, 85 and then drawing the semi-circle 13-4 from the center point 15 of the line 4-13. The remaining portion of the armhole is sketched in by drawing a curve from the point 4 to a point 10 in the line 5-6, which point 10 is 90 located by drawing a line from the point 4 on the base line 1-2 at an angle of 56° thereto, such line being the line 4-10. After the straight line 4-10 is thus drawn, then the curved line 4-10 representing the 95 armhole can be readily sketched in. The lines 8-9, 6-10 as thus developed constitute the shoulder lines of the front and back of the pattern.

The armhole notch where the under arm 100 seam of the sleeve is to come is determined by drawing a line from the point 15 at an angle of approximately 63° from the line 4-13, and where this line cuts the arc 4-13 at the point 18 is the proper point for the 105 armhole notch. To determine the line at the center of the back, I lay off through the point 5 the cross back line 19-20 at an angle of approximately 7° from the base line 1-2, and then one-half of the back measure of the 110

person for whom the pattern is being cut will be laid off on this cross back line from the point 20, thus locating the point 19. The back line 8—22 is then drawn perpendicular to the cross back line 19—20 through the point 19 as thus determined. This gives the total length of the shoulder line 8—9 and also the direction of the back line 8—22.

The bust line 21—23 is drawn parallel to the base line 1—2 and tangent to the arc 4—13. One-half of the bust measure of the person for whom the pattern is being made is laid off on this bust line 21—23 from the point 21 where the bust line intersects the back line 8—22, this being the point 23. The point 6 on the shoulder line 5—6 is located by laying off on this line a distance from the point 10 equal to the distance between the points 8 and 9, and after the point 20 6 and also the point 23 have thus been located the line 6—23 is drawn to provide the proper angle for the front center line. The lines of the front and rear shoulder and body portions of the pattern are thus determined. The lines for the portion of the pattern below the shoulders and bust will, of course, vary, depending on the style and relation between the various measurements of the garment to be made. This same procedure is used in laying out the pattern for any size and proportion, and the only three measurements which are necessary to use for determining the outline of the pattern are the armhole measure, the cross back measure and the bust measure. From these the pattern can be made, as above described, and when a garment is cut by this pattern and the shoulder edges 8—9 and 6—10 are sewed together the garment will have a perfect fit. One advantage of this method is that it enables a dressmaker or tailor to get a perfect fit over the bust regardless of the relative size of the bust and other measurements.

It is a fact that the bust measure of two women who are otherwise of equal proportions may vary greatly, and with my improved method it is possible to draft a pattern perfectly for any woman, regardless of the relation between her bust measure and the other measurements, for by my invention the armhole measure and the shoulder lines 8—9, 6—10 and the back line 8—22 are developed from the armhole size and cross back measure regardless of the bust measure, while the front line 6—23 is developed or determined solely by the bust measure and without regard to the other measurements.

In order to make my invention one which can be easily used I have provided a plate having thereon the various measurements and pattern outlines for patterns having different-sized armhole measurements so that by laying said plate on the paper, cloth or other material from which the pattern

is to be cut, a pattern of the proper size and proportion can be quickly marked out without going through the form of laying off the points and angular lines above described. In Figs. 2 and 3 I have shown at 30 a plate of this character which is a plate of sheet material either metal, cardboard, leather-board, or any other suitable material, and which has therein a plurality of armhole slots 31 representing different sizes of armhole measurements and laid out in accordance with my method above described; which also has therein a plurality of parallel slots 32 which represent the various shoulder lines 8—9 corresponding to the sizes represented by the armhole slots 31; which also has another set of parallel slots 33 representing the shoulder lines 6—10 of the pattern shown in Fig. 1 and representing the front shoulder lines for the armhole sizes indicated by the slots 31. My improved plate also has a plurality of slots 34 representing the bust line for the various armhole slots and another series of slots 35 representing the cross back lines for the various armhole sizes. These various slots may be either continuous slots or intermittent as desired, and they will be numbered to indicate the armhole size which they represent. With this plate above described, therefore, it is possible for anyone after having taken the armhole measure, cross back measure and bust measure to place the plate on the cloth or paper and then to trace through the alternate slots 31, 32, 33, 34 and 35 on the plate corresponding to the armhole measure. This gives the outline for the pattern based on the armhole measure and the pattern can then be completed by laying off the cross back measure and the bust measure corresponding to the person for whom the pattern is made.

The line 16—17 on Fig. 1 designates the center line which defines the front and rear portions of the pattern. This line is drawn through the point 15 perpendicular to the base line 1—2. Since this line is always in a fixed position for every size of pattern it is possible to indicate it on the plate 30 by a single slot 36, as indicated in Fig. 2. The armhole notch 18 is also in a fixed position for every size of pattern, and the single slot 37, therefore, in the plate 30 will give the line of this notch for all sizes of patterns. In using the plate 30 the operator will mark through the slots 36, 37 and then extend the lines so located to make the center line 16—17 on the pattern and also to locate accurately the armhole notch 18.

Referring now to Fig. 4 it will be seen that I have illustrated the outlines of the body and skirt portions of a garment pattern. The outlines of the upper part of the pattern are determined in accordance with the above-described method and the differ-

ent sections of the body and skirt are drawn in according to the desired style of garment and size and proportion of the person and by angular measurements. In outlining these pattern sections in the first instance the skirt portions thereof overlap each other, as shown, but it will be understood, of course, that when the final pattern is taken off the sections of pattern will not have this overlapping relation. These pattern sections include a front center section *a* included between the lines 40 and 41, a front side section *b* included between the lines 42 and 43, a rear side section *c* included between the lines 44 and 45, and a rear center section *d* included between the lines 46 and 47. It will be understood, of course, that the number, shape and proportions of these sections may be varied according to the size and style of the garment.

In order to secure a perfect bottom line to the skirt of the garment, I arrange the pattern sections as shown in Fig. 5. It will be noted and understood that the edges of each of the skirt sections below the hip line are approximately straight and that the two side lines thereof diverge from each other toward the bottom of the skirt. When, therefore, the various pattern sections are arranged with the skirt portions abutting each other, as shown in Fig. 5, the result is a fan-shaped arrangement. In order to get the proper line for the bottom of the skirt, the two outer side edges 41 and 46 are extended until they meet, as at the point 50, and then an arc is struck from this point 50 as a center at a proper distance below the waist line or some other fixed point, this giving the curved line 52 which represents the bottom edge of the skirt. By making this line a true arc of a circle according to this method, it will follow that if the skirt is made in exact accordance with the pattern thus produced the bottom edge of the skirt will hang evenly and the dressmaker or tailor does not need to use a skirt marker or any other means for securing an even hanging of the skirt as is now the usual custom.

The lines 40, 41, 42, 43, 44, 45, 46 and 47 are determined by angular measurements. That is, I first determine the total angle desired between the lines 41 and 46 when the parts of the pattern are laid out as seen in Fig. 5 (an angle of 27° is about the proper angle for an ordinary skirt) and then I divide this angle between the various sections of the skirt pattern according to the style of the garment.

In order to secure a perfect neck line I place the back shoulder portion adjacent the front shoulder portion with the lines 8—9 and 6—10 in alinement. This will bring the line 8—22 of the back shoulder portion at the position defined by the line 6—51. I then extend this line 6—51 to make the line

51—59 and then I lay off on this line 51—59 from the point 6 a distance equal to one-fifth of the neck measure thereby determining the point 53. From the point 53 a line 53—54 is drawn at right angles to the line 51—53, and the point 54 where this line meets the line 6—23 is the point where the neck line begins. I then lay off on the line 6—23 a distance from the point 54 equal to one-sixth of the neck measure thereby determining the point 55, and I then lay off on the line 51—59 from the point 6 a distance equal to the distance 6—55 thereby defining the point 57. The line 57—56 is then drawn. The point 55 is then used as a center to strike the arc 54—56 and the point 57 where the line 55—57 crosses the line 51—59 is used as a center for striking the arc 56—58. This curved line 54—58 gives the true curve for the neck line, the portion 85 of the curve between the line 6—10 and the point 58 being that portion of the neck curve which is on the center back section *d* and this curve can be transferred to this center back section *d* to produce the curve 90 60—61.

By the terms "armhole measure" and "armhole measurement" as used in this description and in the claims I mean the circumferential measurement of the armhole. 95

While I have described one embodiment of my invention I do not wish to be limited to the constructional features herein specified.

Having fully described my invention, what I claim as new and desire to secure 100 by Letters Patent is:—

1. The method of laying out a garment pattern which consists in laying off from a point on a base line distances equal to substantially one-quarter and two-thirds of the 105 armhole measurement thereby to locate the front and rear sides of the armhole and the points from which the two shoulder lines are to be drawn, and then drawing said shoulder lines from said points at angles of 110 approximately 17° and 34°, respectively, to the base line.

2. The method of laying out a garment pattern which consists in laying off from a point on a base line distances equal to substantially one-quarter and two-thirds of the 115 armhole measure thereby to locate the front and rear sides of the armhole and the points from which the front and rear shoulder lines are to be drawn, drawing said front 120 and rear shoulder lines at angles of approximately 17° and 34°, respectively, from said points, and forming the outline of the armhole by arcs struck from different centers determined by measurements based on the 125 armhole measurement.

3. The method of laying out a garment pattern which consists in laying off from a point on a base line distances equal to substantially one-quarter and two-thirds of the 130

- armhole measure thereby to locate the front and rear sides of the armhole and the points from which the front and rear shoulder lines are to be drawn, drawing said front and rear shoulder lines at angles of approximately 17° and 34°, respectively, from said points, forming the outline of the armhole by arcs struck from different centers determined by measurements based on the armhole measurement, and then determining a point for the front line by laying off one-half the bust measure on a line parallel to the base line and drawn tangent to the armhole.
15. 4. The method of laying out a garment pattern which consists in laying off from a point on a base line distances equal to substantially one-quarter and two-thirds of the armhole measure thereby to locate the front and rear sides of the armhole and the points from which the front and rear shoulder lines are to be drawn, drawing said front and rear shoulder lines at angles of approximately 17° and 34°, respectively, from said points, forming the outline of the armhole by arcs struck from different centers determined by measurements based on the armhole measurement, laying off one-half the cross back measurement on a cross back line drawn through the point of intersection of the front shoulder line and the base line at an angle of approximately 7° to the base line, and drawing the back line perpendicular to said cross back line through the point thus determined.
30. 5. The method of laying out a garment pattern which consists in laying off from a point on a base line distances equal to substantially one-quarter and two-thirds of the armhole measure thereby to locate the front and rear sides of the armhole and the points from which the front and rear shoulder lines are to be drawn, drawing said front and rear shoulder lines at angles of approximately 17° and 34°, respectively, from said points, forming the outline of the armhole by arcs struck from different centers determined by measurements based on the armhole measurement, laying off one-half the cross back measurement on a cross back line drawn through the point of intersection of the front shoulder line and the base line at an angle of approximately 7° to the base line, and drawing the back line perpendicular to said cross back line through the point thus determined, the point where said back line meets the rear shoulder line determining the inner end of said shoulder line, and then laying off one-half the bust measure from the back line on a line parallel to the base line and drawn tangent to the armhole.
60. 6. The method of laying out a garment pattern which consists in developing the line for the armhole, shoulder and back from

measurements based on the armhole measure and cross back measure, determining the position of the front line of the pattern from the bust and shoulder measure and then determining the line of the neck by drawing a line through the meeting point of the front line and front shoulder line at an angle to the latter line equal to the angle between the back line and rear shoulder line, laying off on the last-drawn line a distance equal to one-fifth of the neck measure and drawing a line perpendicular to said last-drawn line from the point thus determined, thereby to locate the point of intersection between the neck line and the front line, then laying off on the front line from said latter point a distance equal to one-sixth of the neck measure, drawing a line through the point thus determined in a direction to make equal angles with the front line and the line drawn through the meeting point of said front line and the front shoulder line, and forming the neck line by arcs struck from said latter point and the point of intersection of the line drawn through said point with the line drawn through the meeting point of the front line and shoulder line, respectively.

7. The method of laying out a garment pattern which consists in laying off from a point on a base line distances equal to substantially one-quarter and two-thirds of the armhole measure thereby to locate the front and rear sides of the armhole and the points from which the front and rear shoulder lines are to be drawn, drawing said front and rear shoulder lines at angles of approximately 17° and 34°, respectively, from said points, forming the outline of the armhole by arcs struck from different centers determined by measurements based on the armhole measurement, and drawing the center line perpendicular to the base line through the center of one of said arcs.

8. The method of laying out a garment pattern which consists in laying off from a point on a base line distances equal to substantially one-quarter and two-thirds of the armhole measure thereby to locate the front and rear sides of the armhole and the points from which the front and rear shoulder lines are to be drawn, drawing said front and rear shoulder lines at angles of approximately 17° and 34°, respectively, from said points, forming the outline of the armhole by arcs struck from different centers determined by measurements based on the armhole measure, one of said arcs being a semi-circle and drawing the line for the armhole notch from the center of said semi-circular arc and at an angle of approximately 63° to the diameter thereof.

9. The method of laying out a garment pattern which consists in laying off from a point on a base line distances equal to sub-

stantially one-quarter and two-thirds of the armhole measurement thereby to locate the position of the front and rear of the armhole outline and the points from which the 5 front and rear shoulder lines are to be drawn, drawing said shoulder lines from said points at angles of approximately 17° and 34° , respectively, to the base line, determining the position of the back line and 10 by its intersection with one of the shoulder lines the length of both of said shoulder lines, and then determining the position of the front line of the pattern from the bust measure and the shoulder measure.

15 10. The method of laying out a garment pattern which consists in laying off from a point on a base line distances equal to substantially one-quarter and two-thirds of the armhole measure, thereby to locate the front 20 and rear sides of the armhole and the points from which the front and rear shoulder lines are to be drawn, drawing said front and rear shoulder lines from said points at angles of approximately 17° and 34° , respectively, 25 from the base line, forming the outline of the rear side and bottom part of the armhole by arcs struck from different centers determined by measurements based on the armhole measure, and then drawing 30 a line from the front of the armhole to the front shoulder line at an angle of approximately 56° to the base line thereby to de-

termine the armhole end of the front shoulder line.

11. The method of laying out a garment 35 pattern which consists in laying off from a point on a base line distances equal to substantially one-quarter and two-thirds of the armhole measure, thereby to locate the front and rear sides of the armhole and the points 40 from which the front and rear shoulder lines are to be drawn, drawing said front and rear shoulder lines from said points, striking an arc from the base line at the rear side of the armhole with the point from which the 45 rear shoulder line is drawn as a center thereby to form the rear side of the armhole outline and determine the armhole end of the rear shoulder line, forming the outline of the bottom portion of the armhole by 50 arcs struck from different centers determined by measurements based on the armhole measure, and drawing a line from the front of the armhole and at an angle of approximately 56° from the base line, thereby 55 to determine the armhole end of the front shoulder line.

In testimony whereof, I have signed my name to this specification, in the presence of two subscribing witnesses.

HARRY J. KRAMER.
